(57) **CLAIM**

The ornamental design for an interdental brush, as shown and described.

DESCRIPTION

FIG. 1 is a front view of an interdental brush showing my new design;

FIG. 2 is a left side view thereof;

FIG. 3 is an enlarged top view thereof;

FIG. 4 is an enlarged bottom view thereof;

FIG. 5 is a front view of an embodiment of an interdental brush showing my new design; and,

FIG. 6 is a left side view thereof.

The rear view of FIG. 1 is a mirror image of FIG. 1 and the right side view of FIG. 2 is a mirror image of FIG. 2.

The rear view of FIG. 5 is a mirror image of FIG. 5 and the right side view of FIG. 6 is a mirror image of FIG. 6.

The handle of the interdental brush may comprise two different materials. These two different materials are indicated by the shaded regions and the non-shaded regions in FIGS. 5 to 6. The material of the shaded regions may be softer than the material of the non-shaded regions.

The portions of the interdental brush shown in broken lines form no part of the claimed design.
